UNITED STATES PATENT OFFICE.

PETER M. COPPS, OF HAILEYBURY, ONTARIO, CANADA.

BLASTING-CARTRIDGE.

1,117,794.

Specification of Letters Patent. Patented Nov. 17, 1914.

Application filed April 4, 1914. Serial No. 829,478.

To all whom it may concern:

Be it known that I, PETER M COPPS, a subject of the King of Great Britain, residing at Haileybury, in the district of Nipissing, Province of Ontario, Dominion of Canada, have invented new and useful Improvements in Blasting-Cartridges, of which the following is a specification.

My invention relates to improvements in explosive shells.

One of the objects of my invention is to provide a means by which the shell can be quickly put in place or removed in case of a misfire with less danger to the operator. Another object is to provide a means by which the number of misfires can be considerably reduced.

With these and other objects in view, my invention consists in the novel construction and combination of parts hereinafter more fully described with the aid of the accompanying drawings.

Figure 1 is a side sectional elevation, Fig. 2 a front elevation, and Fig. 3 a detail. 1 designates a shell having a closed end 2 and an open tapped end 3 to receive the threaded plug 4. The plug 4 has a head 5, preferably of square or hexagonal section to allow of its being easily screwed into the shell 1, and also an upwardly projecting lug 6 which has holes 7 and 8. The fuse 9 is held against the lug 6 by a wire 10 or other suitable means, the wire passing through the hole 7 and around the said fuse. The fuse 9 passes downward through the hole 11 in the plug 4, through the felt packing 12 and cardboard packing 13 into the charge 14 and terminates in the cap 15. The draw-wire 16 is hooked through the hole 8, and the end 17 is preferably twisted around the wire 16. A suitable handle 18 may also be formed at the upper end of the draw-wire, which is preferably made of light wire as shown in Fig. 3, so that the end 17 can be easily attached to the lug 6. By means of the draw-wire 16 the shell 1 can be easily lowered into the hole or removed in case of a misfire. As the fuse 9 is held against the

lug 6 by the wire 10 there is very little chance of the fuse slipping and causing a misfire.

From the foregoing it will be seen that a simple and effective means has been devised for expediting the handling of explosive shells, and moreover the construction insures against a large percentage of the misfires experienced with the ordinary shell.

Having thus described my invention, what I claim is:

1. A blasting cartridge comprising in combination, a cylindrical casing adapted to be filled with an explosive element, said cylindrical casing being closed at one end and having a threaded aperture at the other end thereof, a screw plug adapted to fit and close the threaded aperture in said cylindrical casing and having a longitudinally extending drill hole therethrough, a lug carried by said screw plug and positioned at one side of said drill hole, said lug being provided with two transversely extending drill holes, a detonating cap in said cylindrical shell, a fuse connected with said detonating cap and extending upwardly through the longitudinally extending drill hole, a wire disposed in one of said transversely extending drill holes and supporting said fuse against said lug, and a wire disposed in the other of said transversely extending drill hole and provided with a handle at the top thereof whereby the shell may be lifted.

2. A blasting cartridge consisting of a cylindrical casing closed at one end and provided at the other end with a threaded aperture, a threaded plug closing said aperture and having a fuse hole therethrough, a lug carried by said threaded plug, a fuse, a fuse support carried by said lug, and a handle wire carried by said lug.

In testimony whereof I affix my signature in the presence of two witnesses.

PETER M. COPPS.
